UNITED STATES PATENT OFFICE

JAMES E. BLALOCK, OF PACIFIC PALISADES, CALIFORNIA

WRENCH

Application filed July 23, 1928. Serial No. 294,692.

This invention relates to adjustable wrenches, and has for an object the provision of an improved type of adjustable wrench possessed of various meritorious features such as added strength, simplicity of construction and operation, and convenience of adjustment.

A more detailed object is the provision of an adjustable wrench wherein a pair of jaw members are each provided with a shank, these shanks being telescopically received one within the other. The inner shank is exposed through one or more open sides of the outer shank; and a sleeve serving as a handle, is mounted for rotary movement thereupon, this sleeve being provided with means for releasably locking the shanks together with the jaws in adjusted position.

The invention possesses other objects and advantageous features, some of which, with these enumerated, will be set forth in the following description of the invention's particular embodiment which is illustrated in the drawings accompanying and forming a part of the specification.

The form of construction herein disclosed, has in actual use, proven to be very efficient, capable of facile and rapid operation, and generally desirable in other respects. For these reasons, the details herein disclosed may be considered as preferred. It should be mentioned however, that while these details will hereinafter be specifically described, variations may be effected within the scope of the invention as claimed.

Referring to the drawings:

Figure 1 is a side elevation of an embodiment of my invention, portions being broken away and shown in section to better disclose the nature of the invention.

Fig. 2 is a longitudinal, medial sectional view of the wrench of Fig. 1.

Fig. 3 is a bottom plan view, the direction of view being indicated by the arrow 3 of Fig. 1.

Fig. 4 is an enlarged horizontal sectional view, the plane of section being taken upon the line 4-4 of Fig. 1, and the direction of view being indicated by the arrows.

Fig. 5 is a slightly enlarged view in eleva-

tion, of the lower end of the wrench showing the spring latch for retaining the locking sleeve in selected position.

Fig. 6 is a horizontal sectional view taken upon the line 6-6 of Fig. 5, with the direction of view indicated by the arrows.

Fig. 7 is an enlarged fragmentary sectional view, the plane of section being indicated by the line 7-7 of Fig. 1, and the direction of view by the arrows, but showing the moving parts of the wrench, moved to the opposite extreme of their relative movement from that of Fig. 1.

Specifically describing the invention in its present embodiment, I have provided a pair of jaw members 11 and 12, each of which is provided with a pair of opposed gripping faces 13, 14, and 16, 17, respectively. The faces 13 and 16 are opposed to each other as are the faces 14 and 17; but the faces 13 and 16 are spaced a greater distance to increase the range of adaptability of the wrench.

The jaw members 11 and 12 are provided with shanks 18 and 19 respectively, extending therefrom preferably perpendicular to the planes of the gripping faces. The shank 18 extends slidably through an aperture 21 in the jaw member 12, and is telescopically received within the shank 19. The shank 19 is open upon opposite sides, producing in effect, a pair of spaced legs 22 between which the shank 18 is slidably received.

The inner and outer shanks 18 and 19 respectively, together are circular in cross section as best shown upon Fig. 4, and are provided with segmental teeth 23 and 24 respectively, these teeth being arranged concentrically. In their preferable form, the teeth 23 and 24 are spaced from each other, leaving channels 26 therebetween; and the channels 26 correspond substantially in width to the length of the teeth.

A sleeve 27 is mounted for rotary movement upon the outer shank 19, being locked against longitudinal movement thereupon by being restricted between a shoulder 28 and a spring washer 29 which is retained in position against the lower end of the sleeve 27 by a nut 31 threaded onto the lower ends of the legs 22 of the shank 19. Inasmuch as

the nut 31 is tightened so as to be rigid with the legs 22 of the shank 19, it serves as a head thereupon, preventing displacement of the sleeve 27 and washer 29. The washer 29 is 5 provided at one end with a projection 32 received within a socket 33 in one of the legs 22 to prevent rotation of the washer 29 thereupon; and the other end of the washer 29 is provided with a rounded tongue 34 receivable 10 within either of two sockets 36 in the lower end of the sleeve 27. The sockets 36 are spaced a distance equal to the maximum rotation of the sleeve 27, it being understood that the natural resiliency possessed by the 15 spring washer 29 will permit disengagement of the tongue 34 from one of the sockets 36 when it is desired to turn the sleeve 27 and snap the tongue 34 into the other socket 36 when the sleeve has been rotated to the extent 20 of its movement.

A notch 37 is formed in the upper end of the sleeve 27, and a pin 38, rigid with the outer shank 19, is adapted to engage the ends of the notch 37 to restrict rotation of the 25 sleeve.

The sleeve 27 is provided upon its inner circumference, with segmental teeth 41 similar to the teeth 23 and 24, and adapted to be engaged therewith to lock the shanks 18 and 30 19 against relative motion. The teeth 41 are of such length that they may optionally be disposed within the channels 26 between the teeth 23 and 24, to permit adjustment of the jaws 11 and 12; or engaged with the teeth 35 23 and 24 to lock the jaw members in adjusted position, it being understood that this shifting of the sleeve 27 is effected by rotating it to either extreme of its movement as determined by the length of the notch 37.

40 Means are provided for limiting the separation of the jaws 11 and 12 to prevent inadvertent disassembly thereof when adjusting the jaws to vary the effective distance therebetween. A spring lock 43 is secured by a 45 screw 44 or its equivalent, to the inner shank 18 within a recess 46 formed in the side thereof. The other end 47 of the spring lock 43, is bent upwards and outwards to engage against the top 48 of an aperture 49 formed 50 in the jaw member 12 in position to be brought into register with the recess 46 when the jaw members have been moved to their position of greatest separation. Since the end 47 of the spring lock 43 is inclined upwards and outwards, it will snap into the aperture 49 and engage the top 48 thereof when the shank 18 has been withdrawn from the shank 19 sufficiently to bring the aperture 49 and recess 46 into register, but will engage 55 the bottom 51 of the aperture 49 when the jaw member 11 is again forced toward the jaw member 12, springing the end 47 inside the shank 19 so that collapsing of the wrench is not restricted thereby.

60 The outside of the sleeve 27 is roughened as

by knurling 52, since it is intended that the sleeve 27 shall be employed as the handle of the wrench.

It is thought that the operation of the wrench of my invention will be obvious from the above description of its operative parts. When it is desired to alter the distance between the jaw faces 13 and 16, or 14 and 17, depending upon the size of the member which it is desired to grip with the wrench, the sleeve 27 should be turned upon the shank 19 to the position indicated upon Fig. 4. The pin 38 will engage one end of the notch 37 to limit the rotation of the sleeve so that the teeth 41 thereof will be positioned within the channels 26 between the teeth 23 and 24. The rounded tongue 34 will then spring into the associated notch 36 to resiliently retain the sleeve 27 in this position.

Since the teeth 23 and 24 are not engaged by the teeth 41 of the sleeve 27 when in this position, the jaw member 11 may be adjusted in respect to the jaw member 12, to any desired degree of separation within the limits of the particular size of wrench employed. When the jaw member 11 has been positioned in respect to the jaw member 12 to satisfactorily space the gripping faces, the sleeve 27 should be rotated in the reverse direction. It will be found that the natural resiliency of the spring washer 29 will permit the rounded tongue 34 to unseat itself from the notch 36 and permit such rotation of the sleeve 27. This will effect engagement of the teeth 41 with the teeth 23 and 24 of the shanks 18 and 19 respectively. As a result, the two shanks will be positively locked together to prevent relative movement thereof, and of the jaw members 11 and 12.

At the end of this reverse rotation of the sleeve 27, the pin 38 will engage the other end of the notch 37 to limit rotation of the sleeve, at which time the rounded tongue 34 will snap into the other notch 36 to resiliently retain the sleeve 27 in selected position so that the wrench may now be employed to accomplish the desired work, with the jaw members 11 and 12 positively locked against relative movement.

I claim:

1. A wrench comprising a pair of jaw members adjustable in respect to each other to vary the distance therebetween, a shank rigid with each jaw member, a sleeve mounted for rotary movement upon said shanks, means for locking one of said shanks against longitudinal movement within the sleeve, means releasable upon rotation of the sleeve for locking the other shank against longitudinal movement within the sleeve, a head on said first mentioned shank, and a spring washer interposed between an end of said sleeve and said head to releasably retain said sleeve in selected position.

2. A wrench comprising a pair of jaw

members adjustable with respect to each other to vary the effective distance therebetween, a shank rigid with each jaw member, the shank of the upper jaw member being non-rotatively telescopically received within the other shank and the outer shank being open along a side to expose the inner shank therethrough, a sleeve mounted for rotary movement only upon one of said shanks with the associated shank extending through the sleeve, and means interposed between the sleeve and the other shank for releasably locking them against relative longitudinal motion.

3. A wrench comprising a pair of jaw members adjustable in respect to each other to vary the effective distance therebetween, a shank rigid with each jaw member, the shank of the upper jaw member being telescopically received within the other shank and the outer shank being open along opposite sides to expose the inner shank therethrough, segmental teeth disposed upon opposite sides of said inner shank and extending through said open sides of the outer shank, similar teeth on said outer shank, the teeth on said shanks being separated to leave channels therebetween, a sleeve mounted for rotary movement upon said outer shank, and complementary segmental teeth on said sleeve adapted to engage the teeth on both shanks or to be disposed within said channels.

4. A wrench comprising a pair of jaw members adjustable in respect to each other to vary the effective distance therebetween, a shank rigid with each jaw member, the shank of the upper jaw member being telescopically received within the other shank and the outer shank being open along opposite sides to expose the inner shank therethrough, segmental teeth disposed upon opposite sides of said inner shank and extending through said open sides of the outer shanks, similar teeth on said outer shank, the teeth on said shanks being separated to leave channels therebetween, a sleeve mounted for rotary movement upon said outer shank, complementary segmental teeth on said sleeve adapted to engage the teeth on both shanks or to be disposed within said channels, and resilient means for retaining the sleeve in selected position.

5. A wrench comprising a pair of jaw members adjustable in respect to each other to vary the effective distance therebetween, a shank rigid with each jaw member, the shank of the upper jaw member being telescopically received within the other shank and the outer shank being open along opposite sides to expose the inner shank therethrough, segmental teeth disposed upon opposite sides of said inner shank and extending through said open sides of the outer shank, similar teeth on said outer shank, the teeth on said shanks being separated to leave channels therebetween, said channels substantially corresponding in width to the length of said teeth,

a sleeve mounted for rotary movement upon said outer shank, and complementary segmental teeth on said sleeve adapted to engage the teeth on both shanks or to be disposed within said channels.

6. A wrench comprising a pair of jaw members adjustable in respect to each other to vary the effective distance therebetween, a shank rigid with each jaw member, the shank of the upper jaw member being telescopically received within the other shank and the outer shank being open along opposite sides to expose the inner shank therethrough, segmental teeth disposed upon opposite sides of said inner shank and extending through said open sides of the outer shank, similar teeth on said outer shank, the teeth on said shanks being separated to leave channels therebetween, a sleeve mounted for rotary movement upon said outer shank, complementary segmental teeth on said sleeve adapted to engage the teeth on both shanks or to be disposed within said channels, resilient means for retaining the sleeve in selected position, and a stop interposed between said shanks to limit the separation of said jaw members.

In testimony whereof I have signed my name to this specification.

JAMES E. BLALOCK.
